UNITED STATES PATENT OFFICE

JAMES W. DECKER, OF NEW YORK, N. Y.

STOCK QUOTATION PROJECTING MACHINE

Application filed May 19, 1928, Serial No. 278,982. Renewed May 24, 1932.

This invention relates to stock quotation projecting machines in general.

Among the objects of the present invention it is aimed to provide a stock quotation projecting machine including a ticker, projecting apparatus and a pneumatic device for absorbing the vibrations transmitted to the tape by the ticker before the tape reaches the projecting machine.

10 It is also an object of the present invention to provide a stock quotation projecting machine including a ticker, projecting apparatus, a tape drawing device, and a pneumatic device for absorbing the vibrations transmitted to the tape by the ticker before the tape reaches the projecting machine and also to actuate the tape drawing means.

20 These and other features, capabilities and advantages of the present invention will appear from the subjoined detail description of one specific embodiment thereof illustrated in the accompanying drawing in which

25 Figure 1 is an elevation diagrammatically showing the connections of the several elements; and

Fig. 2 is a fragmental detail plan of the mouth of the air discharge.

In the embodiment illustrated, the tape A is ejected from the ticker T and from there passes between the idlers 1 and 1', then to the idlers 2 and 2', and then to the light aperture or light receiving station 3 from which the tape A passes between the idlers 4 and 4' down to the tape drawing roller 5 into engagement with which the tape A is maintained by the idler 6.

30 In this mechanism, images of the quotations printed on the tape A by the ticker T are projected through the projecting lens contained in the housing 7 to a screen not shown similar to the projecting apparatus shown and illustrated in my copending application Serial No. 253,302.

40 The present invention relates mainly to absorbing the vibrations transmitted by the ticker to the tape so that the tape will pass through the projecting station 3 in a comparatively smooth manner. If such vibrations are not dissipated before the tape passes

into the projecting station 3, these vibrations will be projected with the quotations magnified several times. When so magnified, the vibrations will of course be accentuated to such an extent as to interfere with the reading of the projections on the screen. An inspection of the screen for any length of time when such vibrations are not dissipated will obviously cause the observer an objectionable eye strain.

60 The device here provided for dissipating the vibrations or absorbing the vibrations is a pneumatic device which will now be described.

An air pressure tank 8 is connected by the 65 conduit 9 with the tape supporting disk 10 in which there is provided a small air passage. By means of the air pressure being stored in the tank 8, the air therefrom will issue through the disk 10 to deflect the tape A into a loop in which loop the vibrations from the ticker will be absorbed. The air pressure will have the effect of causing the tape to cooperate with the idler 2 to press the tape against such idler 2 which will 70 serve as a friction creating device to engage the tape and interrupt the vibrations transmitted thereto by the ticker, in the same manner as the finger of a musician will interrupt the vibrations on a violin string.

75 The air tank 8 is supplied with air by means of the air pump 11 which is connected to the air tank by the conduit 12. The air pump 11 is provided with a gear 13 in mesh with the gear 14 on the shaft 15 of the motor 16. The motor 16, in the present instance, is connected by the conductor 17 with the outlet 18, which outlet 18 is connected by the conductor 19 with the switch contact 20. The switch contact 20 is adapted to cooperate 80 with the movable contact 21 pivoted at 22, which contact 21 is connected by the conductor 23 with the motor 16. The movable contact 21 has the projection 24 of one of its arms 25 positioned in the recess 26 of the disk 27 pivoted on the shaft 28. The disk 27 is connected by the link 29 with the link 30 pivoted to the housing 31 of a pressure regulator.

95 100 The pressure regulator has a stem 32 slid-

ably mounted thereon and provided with a pressure sensitive diaphragm 33. Between the diaphragm 33 and the upper end of the housing 31, the stem 32 is provided with a 5 compression spring 34 for exercising a downward pressure on the diaphragm in opposition to the pressure contained in the tank 8 which passes to the diaphragm by means of the conduit 35. Associated with the conduit 10 9 there is provided a turbine 36 propelled by the air pressure passing through the conduit 9. Such turbine 36 is provided with a shaft 37 on which is mounted a pulley 38 which is connected by the belt 39 with the 15 pulley 38', fixed to the drawing roller 5.

The diaphragm 33 and spring 34 will be adjusted so that when the passage of air is stopped from issuing through the disk 10, sufficient pressure will be developed to deflect the diaphragm 33 upward, thereby to 20 actuate the lever 29 to rotate the disk 27 to bring the movable contact 21 out of engagement with the fixed contact 20 when the current to the motor 16 will be cut off in turn to cause the air pump 11 to be stopped. At 25 the same time the turbine 36 will also be arrested thereby to stop the drawing roller 5.

The position of the tape A so that it will 30 shut off the opening through the disk 10 will be effected only when the ticker T stops, at which time the roller 5 will continue to draw the tape until the slack in the tape at the position 40 above the disk 10 has been taken up in turn to cause the tape to lie flat 35 against the disk 10.

As soon as the ticker T again starts to 40 transmit messages in turn to eject the tape A, the tape A will first form slack at the location 40 to open the passage of air through the disk 10 and permit the air pressure in the tank 8 to discharge. As the same discharges and the pressure reduces sufficiently to permit the diaphragm 33 to assume its 45 normal position, it will withdraw the lever 29 to actuate the disk 27 in turn to actuate the movable contact 21 into engagement with the fixed contact 20 when the current to the motor 16 will be established to cause the motor to be actuated in turn to cause the air 50 pump 11 to be actuated. As soon as the air is discharged through the conduit 9, it will actuate the turbine 36 to actuate the tape drawing roller 5.

It is obvious that various changes and 55 modifications may be made to the details of construction without departing from the general spirit of the invention as set forth in the appended claims.

I claim:

60 1. The combination with a ticker tape, of a tape drawing device for drawing the tape across the light aperture of a projecting machine, pneumatic means cooperating with the tape before it enters the light aperture for 65 dissipating the vibrations transmitted to the

tape before the tape passes to the light aperture, and an air motor for actuating said tape drawing device, said pneumatic means supplying pressure normally to actuate said air motor.

70

2. The combination with a ticker tape, of a tape drawing device for drawing the tape across the light aperture of a projecting machine, means for actuating said tape drawing device, a pressure tank, and a device for feeding pressure from said pressure tank to the tape at the entrance end of said light aperture to form a loop to dissipate the vibrations transmitted to the tape before the tape passes across the light aperture, said device also feeding such pressure to said actuating means to control the same.

75

3. The combination with a ticker tape, of a tape drawing device for drawing the tape across the light aperture of a projecting machine, a pressure tank, a conduit connected to said pressure tank, an apertured disk at the end of said conduit disposed at the entrance end of said light aperture to be engaged by said tape to close the aperture when the tape supply is arrested, the aperture being open when the tape supply operates to permit the air pressure from said tank to blow onto said tape and form a vibration absorbing loop, a turbine operatively connected to said conduit, and driving means connecting said turbine with said drawing device.

80

4. The combination with a ticker tape, of a tape drawing device for drawing the tape across the light aperture of a projecting machine, a pressure tank, a conduit connected to said pressure tank, an apertured disk at the end of said conduit disposed at the entrance end of the light aperture to be engaged by said tape to close the aperture when the tape supply is arrested, the aperture being open when the tape supply operates to permit the air pressure from said tank to blow onto said tape and form a vibration absorbing loop, an air pump connected to said pressure tank to supply pressure thereto, a motor connected to said air pump, a switch operatively connected to said motor, a switch controlling device operatively associated with said pressure tank to open said switch when the pressure rises in said tank due to the closing of the aperture in said disk, a turbine operatively connected to said conduit, and driving means connecting said turbine with said drawing device.

90

5. The combination with a ticker tape, of a tape drawing device for drawing the tape across the light aperture of a projecting machine, a pressure tank, a conduit connected to said pressure tank, an apertured disk at the end of said conduit disposed at the entrance end of the light aperture to be engaged by said tape to close the aperture when the tape supply is arrested, the aperture being open when the tape supply operates to

95

100

105

110

115

120

125

130

permit the air pressure from said tank to blow onto said tape and form a vibration absorbing loop, an air pump connected to said pressure tank to supply pressure thereto, a 5 motor connected to said air pump, a turbine operatively connected to said conduit, and means for operatively connecting said tape drawing device to said turbine to be driven thereby.

10 6. The combination with a ticker tape, of a tape drawing device for drawing the tape supplied thereto across the light aperture of a projecting machine, spaced tape guiding means formed at the entrance end of the light 15 aperture, and pneumatic means for exercising pressure on the tape between said guiding means to form a loop when the tape supply operates and cooperating with said guiding means to dissipate the vibrations transmitted 20 to the tape before the tape passes to the light aperture.

7. The combination with a ticker tape, of a tape drawing device for drawing the tape supplied thereto across the light aperture of 25 a projecting machine, spaced pressure rollers engaging the tape at the entrance end of the light aperture, and pneumatic means for exercising pressure on the tape between said spaced pressure rollers to form a loop when 30 the tape supply operates to cooperate with said pressure rollers to dissipate the vibrations transmitted to the tape before the tape passes to the light aperture.

8. The combination with a ticker tape, of 35 a tape drawing device for drawing the tape across the light aperture of a projecting machine, an air motor, means for operatively connecting the air motor to actuate said tape drawing device, and means cooperating with 40 the tape to control the pressure supply to said air motor.
